Patented Mar. 5, 1974

230,600

COMBINED DEPTH FINDER AND FISH LOCATOR

Robert F. Turner, El Paso, Tex., assignor to Jetco
Electronic Industries, Inc., El Paso, Tex.

Filed Jan. 28, 1972, Ser. No. 221,851

Term of patent 14 years

Int. Cl. D10—04

U.S. Cl. D26—1 Q

FIG. 1

FIG. 2

FIG. 3

FIG. 4

FIG. 5

FIG. 1 is a front perspective view of a combined depth finder and fish locator showing my new design;

FIG. 2 is a front elevational view thereof;

FIG. 3 is a rear elevational view thereof;

FIG. 4 is a left side elevational view thereof, the right side being a mirror image thereto;

FIG. 5 is a bottom plan view thereof.

I claim:

The ornamental design for combined depth finder and fish locator, substantially as shown and described.
